HAIR DRIER

Reuben A. Olsen, Excelsior, Minn.

Application December 9, 1932, Serial No. 646,380

7 Claims. (Cl. 34—26)

This invention relates to driers of the general type employed in beauty parlors and barber shops for drying the scalp and hair after shampooing, washing, or other treatments have been given, 5 and the main object is to provide an efficient, practical, and highly novel construction of mechanism or drier unit for that purpose. Other more detailed and specific objects will be disclosed in the course of the following specification, reference being had to the accompanying drawing, 10 wherein:

Fig. 1 is an enlarged sectional elevation taken diametrically through the drier unit.

Fig. 2 is a cross sectional view as seen substantially on the irregular line 2—2 in Fig. 1.

The structure of the drier unit includes a dome shaped housing or outer shell 8 which carries the entire drying mechanism, and is in turn supported on a portable standard or other support, 20 the details of which form no part of the present invention. Spaced within the housing 8 are two inner shell-like members 9 and 10, the latter of which may be referred to as a mask or inner dome, and it is the enclosure defined by this dome 25 that receives or is placed over the head having the hair to be dried. The lower portions of the shell-like members 8, 9, and 10, are concentrically spaced with respect to each other to provide an inner annular chamber 11 and an outer annular chamber 12, and the lower ends of these 30 chambers are closed by an integral flange portion 13 of the dome 10 which extends outwardly as shown in Fig. 6 to receive the lower end edges of the members 8 and 9.

The inner annular chamber 11 terminates above the dome 10 in a relatively large central chamber 14, in which operates a fan or blower 15. The fan 15 is of the propeller or radial thrust type, and when operated functions to create a down 40 draft of air about the dome 10 and into the interior thereof through a series of spaced holes 16. The air thus passing through the holes or ports 16 to the interior of the mask 10 is not discharged from the unit, however, but is diverted back through openings 17 which are defined by short sleeves or collars 18 that connect the members 9 and 10 at spaced points so as to direct the return flow of air into the annular chamber 12 and without permitting it to in any 45 way re-enter the annular chamber 11. Thus it will be seen that the air current created by the fan 15 will pass into the interior of the dome 10 at spaced points about the head having the hair to be dried, and after being briefly circulated 50 through such hair is then withdrawn through

the openings 18 at other spaced points, and from thence passes up through the annular chamber 12, all as indicated by the direction arrows.

At its upper end the intermediate shell 9 is rigidly secured to an annular cast rim 19 which in turn is provided with circumferentially spaced radial lugs or spokes 20 that fit snugly within the housing 8 and are rigidly secured therein as by screws 21. These screws not only secure the rim 19, but also operate through the rim to releasably secure the entire drying mechanism within the housing 8, and consequently when these screws are removed the entire drier structure can be bodily removed downwardly out of the housing 8.

An air deflecting cup 22 extends axially down within the rim 19 and into the chamber 14. This cup 22 has a wide flange 23 at its upper end which is spaced above the rim or ring 19, and is rigidly secured in this spaced relationship by 20 spacer lugs 24 and screws 25. Spaced within the cup 22 and tapering downwardly to conform with the contour thereof, is an upwardly extending sleeve 26 which is rigidly secured to the cup as at 27, and is sufficiently spaced from the 25 cup to provide an annular passageway 28 for the circulation of a secondary air current, as will presently be described.

Mounted within the sleeve 26 is the operating motor 29 having a spindle 30 at its lower end for 30 supporting the main fan 15, and at its upper end the motor shaft has a secondary fan 31 which operates within the upper end of the sleeve 26. The purpose of the fan 31 is to draw relatively cool air down through openings 32 in the upper end of 35 the housing 8, and move it downwardly within the sleeve 26 to cool the motor 29. After cooling the motor the secondary air current passes down into the cup 22, up through the annular space 28, and over the cup flange 23 to a restricted annular 40 passageway 33 between the flange 24 and the housing 8. At this point the secondary air current which has become partially heated by the motor 29 is taken up and absorbed by the main air current which is passing up through the annular chamber 12 inwardly over the ring 19, and thence downwardly into the chamber 14, to be recirculated through the openings 16 and 17 as has already been described.

In order to raise the temperature of the primary air current I provide a pair of heating elements in the form of circular coils 34 which are suitably mounted and insulated, and which are so arranged that they will intersect the air current passing inwardly under the flange 24 and 55

downwardly about the cup 22. A conveniently arranged switch 35 is connected with the heating unit 34 and is also preferably connected with the motor 29 so that one switch may be employed 5 to control both electric members, and thus also insure energization of the heating elements whenever the motor is put in operation.

From the foregoing it will readily be seen that when the switch 35 is closed the motor 29 will immediately put the fans 15 and 31 in motion, whereupon the primary and secondary air currents will be created, and as soon as the heating elements 34 begin to function the primary air current will be heated thereby to thus increase the 15 drying efficiency of the structure.

It will be understood that suitable modifications may be made in the structure as disclosed, provided such modifications come within the spirit and scope of the appended claims. Having now 20 therefore fully illustrated and described my invention, what I claim to be new and desire to protect by Letters Patent is:

1. A drier of the character described comprising an outer housing, an inner hood having inlet 25 and outlet openings, a fan for circulating air through the openings, a shell member disposed intermediate said housing and hood to form annular chambers therebetween, said outlet openings being defined by tubular members connecting said 30 hood and shell and extending through the inner of said annular chambers to establish independent communication between the hood and the outer of said chambers.

2. In a drier the combination comprising a 35 housing having an apertured hood mounted in one end thereof, a partitioning shell extending from adjacent the base of the housing with its upper end edge remote from the hood, a cup member positioned in the upper end of the shell 40 and having a flange portion spaced therefrom to provide an annular restricted passageway between such shell end edge and the cap flange portion, and a motor and fan carried by the cup for producing a positive circulation of air inwardly 45 through said restricted opening and thence downwardly to the apertured hood.

3. In a drier the combination comprising a 50 housing having an apertured hood mounted in one end thereof, a partitioning shell extending from adjacent the base of the housing with its upper end edge remote from the hood, a cup member positioned in the upper end of the shell and having a flange portion spaced therefrom to provide an annular restricted passageway between 55 such shell end edge and the cup flange portion, means for producing an air circulation inwardly through said restricted opening and downwardly to the apertured hood, and an electric heating element arranged between the cup member and 60

the adjacent end of the partitioning shell to heat the air circulated through therebetween.

4. A drier of the character described comprising a housing having a hood in one end thereof provided with inlet and outlet openings, a partitioning shell defining inner and outer chambers respectively communicating with the hood, a flanged cup member secured to the upper end of the partitioning shell and spaced therefrom to provide a connecting passageway as between said 10 chambers, and a power driven fan in the inner chamber.

5. A drier of the character described comprising a housing having a hood in one end thereof provided with inlet and outlet openings, a partitioning shell defining inner and outer chambers respectively communicating with the hood, a flanged cup member secured to the upper end of the partitioning shell and spaced therefrom to provide a connecting passageway as between said 20 chambers, and spaced from the housing to provide a second restricted passageway, a motor arranged in the cup member to drive a main fan disposed thereunder, and a second fan driven by and for cooling the motor, said second fan being disposed 25 above the cup member and adapted to circulate air through said second restricted passageway.

6. A drier of the character described comprising a housing having a hood in one end thereof provided with inlet and outlet openings, a partitioning shell defining inner and outer chambers respectively communicating with the hood, a flanged cup member secured to the upper end of the partitioning shell and spaced therefrom to provide a connecting passageway as between said 35 chambers, and spaced from the housing to provide a second restricted passageway, a motor arranged in the cup member to drive a main fan disposed thereunder, a sleeve about the motor, and a second fan operated by the motor and arranged to circulate air through the sleeve.

7. A drier of the character described comprising a housing having a hood in one end thereof provided with inlet and outlet openings, a partitioning shell defining inner and outer chambers 45 respectively communicating with the hood, a flanged cup member secured to the upper end of the partitioning shell and spaced therefrom to provide a connecting passageway as between said chambers, and spaced from the housing to provide a second restricted passageway, a motor arranged in the cup member to drive a main fan disposed thereunder, a sleeve about the motor, and a second fan operated by the motor and arranged to circulate air through the sleeve, said 50 sleeve being projected down into the cup member but spaced therefrom to provide an annular air passageway.

REUBEN A. OLSEN.
